United States Patent Office

Des. 176,257
Patented Dec. 6, 1955

176,257

COMBINATION FOOD AND DRINK MIXER BASE

Joseph A. Hill, Glen Ellyn, Ill., assignor to John Oster
Manufacturing Company, Milwaukee, Wis., a corporation of Wisconsin

Application June 14, 1954, Serial No. 30,975

Term of patent 14 years

(Cl. D89—1)

Fig. 1.

Figure 1 is a perspective view of a combination food and drink mixer base embodying my new design;

I claim:

The ornamental design for a combination food and drink mixer base, as shown.
